his Attorney.

UNITED STATES PATENT OFFICE.

WILL M. KINNARD, OF DAYTON, OHIO.

BOOK-LEVELER.

SPECIFICATION forming part of Letters Patent No. 389,891, dated September 25, 1888.

Application filed March 12, 1888. Serial No. 266,970. (No model.)

To all whom it may concern:

Be it known that I, WILL M. KINNARD, a citizen of the United States, residing at Dayton, in the county of Montgomery and State 5 of Ohio, have invented certain new and useful Improvements in Book-Levelers, of which the following is a full, clear, and exact description, reference being had to the accompanying drawings, forming part of this specification.

My invention relates to an improvement in book-levelers to be applied to books used for recording or writing, for the purpose of preserving both pages of the open book at the 15 same or substantially the same level. Where writing is to be done in a large thick book, if the book is opened at or near the middle, both pages will be at about the same level; but if opened at or near the beginning or end one 20 page will be much higher, and in order to do good work or write easily it is necessary to raise the lower portion of the book and support it at a height or level corresponding with the other portion.

25 My invention consists in providing an adjustable support for that purpose which shall be attached to or form a part of the cover of the book, always at hand for use, or, when not in use, incased in the cover of the book and out 30 of the way.

In the accompanying drawings, Figure 1 is a perspective view of an open book with my adjustable leveler in position of use. Fig. 2 is a vertical longitudinal section of the cover 35 or lid of a book and the leveler. Fig. 3 is a plan view of the outside of the book with the leveler shut up or incased in the lid or cover. Figs. 4 and 5 are details of construction shown in Fig. 2. Fig. 6 is a cross-section showing 40 adjusting device.

Like letters of reference indicate identical parts in all the figures.

A A' are the pages of an open book as the book is shown opened near the beginning. 45 Without some support the page A would be at a lower level than the page A'.

B is the cover or lid of the book. In the outside of this lid or cover B is cut a groove or slot, F, to receive the leveler, which 50 consists of the narrow plate or arm C C'. The two arms are hinged together at D, so as to form an elbow. Along the sides of the groove

F, I provide two parallel plates, H H. These plates H H are sunk into the lid so as to be flush with its outside surface, and are sufficiently far apart to receive between them the arm C C'. The end of the arm C is pivoted to the lid of the book by means of the hinges on the plates H H, as shown at K, Fig. 4, or in any convenient way, while the free end of the arm C' slides between the plates H. Beneath the plates H H are springs L L, to which the end of the arm C' is attached by pins l. These springs press against the under or inside of the plates H H and force the end of the arm C' down into the ratchet P, provided along the bottom of the groove or slot F. Of course any convenient form of spring may be used for holding the arm C' against the ratchet. As the arm C C' is bent at the joint or elbow D into the position shown in Fig. 2, the free end of the arm C' slides along on the ratchet P, engaging with it at whatever point it may be desired and holding the arm bent at any desired angle. The elbow D, resting against 75 the desk on which the book is supported, lifts and supports the lid or cover B at whatever point is necessary to bring the page A on the same level with page A'.

When the leveler is not in use, it lies straight 80 or flat in the slot, as shown in Fig. 3, flush with the outside of the book, entirely out of the way.

For the more convenient adjustment of the leveler C C', I provide on the inside of the lid 85 a little button or thumb-piece, R, whose neck or shank slides in a narrow slot along the inside of the cover parallel or corresponding with the slot or groove F. The lower end of this shank is attached to the free end of the 90 arm C', so that by pressing upon the button R the springs L L are depressed and the arm C' freed from the ratchet to be adjusted at any point. The pressure on the button being then released, the arm C' at once engages with the 95 ratchet and secures the leveler in position. A similar leveler can of course be used in each cover or lid, and may be modified in shape and details of construction. The spring also may be dispensed with, if desired, as the weight of 100 the book will always hold the arm against the ratchet P, though I prefer to use it with a spring.

Having thus fully described my invention,

what I claim, and desire to secure by Letters Patent, is—

1. An adjustable lever for raising the cover and leaves of an open book, consisting of a hinged arm incased within the cover of the book, its free end arranged to engage with a ratchet for adjusting and holding it in position, substantially as and for the purpose described.
- 10 2. A book-leveler for leveling the cover and leaves of an open book, consisting of a hinged arm, C C', sunk in the lid of the book when not in use, and capable of being bent out and adjusted at any desired angle, substantially as and for the purpose described.
- 15 3. A book-leveler for leveling the cover and leaves of an open book, consisting of a hinged arm, C C', pivoted to the cover of the book, in combination with the plates H H, ratchet P,

and springs for holding the arm C' in engagement with the ratchet, substantially as and for the purpose described.

4. A book having its cover or covers provided with adjustable arms for leveling the pages of the book when open, and sunk in the lid of the book when not in use, and adjustable by means of a ratchet and spring, substantially as described.

5. An adjustable arm for leveling the cover and leaves of an open book, sunk in the lid of the book, and arranged to be drawn out and adjusted at any height, substantially as and for the purpose described.

WILL M. KINNARD.
